THEODORE J. SCOFIELD, OF JACKSON, MICHIGAN, ASSIGNOR TO THE SPARKS-WITHING-
TON CO., OF JACKSON, MICHIGAN, A CORPORATION OF OHIO

ELECTROLYTIC CONDENSER AND HOLDER THEREFOR

Application filed January 14, 1930. Serial No. 420,649.

This invention relates to holders for electrolytic condensers and similar devices.

An object of the invention is to so construct a holder that the condenser, or other container, will permit the ready insertion and removal of the condenser or other device without manipulation of screws, clamps or other holding devices.

Another object of the invention is to construct a holder for electrical devices, such as the condenser above referred to, so that the conductors leading thereto may be held in place with the device in position but which may be handily inserted or removed when the device is not in the holder.

Other objects will appear in the appended description, reference being had to the drawing in which:

Fig. 1 is a sectional view of an electrolyte container.

Fig. 2 is a top view of the cover of the electrolyte container.

Fig. 3 shows the manner of stamping the supporting base to form a holder for the electrolytic condenser.

Fig. 4 is an elevation of the holder shown in Fig. 3 with the spring clips forced into position to receive the container.

Fig. 5 is an edge view of the holder shown in Fig. 4.

Electrolytic condensers are commonly employed in radio receiving sets, particularly in the power apparatus of such sets. Great difficulty has been experienced with these condensers as heretofore made, due to the manner in which the cover of the container is sealed. In most cases the electrolyte has been able to leak out around the electrolyte terminals and through unsealed portions at various places in the cover. In my improved condenser this difficulty has been overcome.

In Fig. 1 reference character 1 indicates a container for the electrolyte of the condenser, which, of course, also houses the electrodes of the condenser. These electrodes are not shown but they are a continuation of the electrode terminals 2 and 3.

The container 1 may be drawn from a single piece of appropriate metal to form an integral bottom with the sides of the container

or the bottom may be made from a separate piece of metal as shown in Fig. 1. The container 1 in the latter case may be formed of a sheet of metal rolled into cylindrical form and seamed together along the sides. The base may be stamped, as shown and forced into the bottom of the container, after which it is either soldered or welded thereto to make it leak-proof.

The electrodes 2 and 3 will pass through the holes 12 and 13 in the rubber material 15 molded and vulcanized to the cover 4. The nuts 18 and 19 may be threaded on these terminals to compress gaskets 20, 21, tightly against the molded material to prevent leakage. Filler cap 22 may be threaded in the hole 14 in the molded material and a tight joint will be formed through the use of gasket 23. If necessary, vent holes may be formed in this cap in such a way as to prevent spilling of the liquid.

The cover plate 4 after it is placed in position may be soldered or welded at its edges to the cylindrical portion 1.

An electrolytic condenser constructed as described forms an excellent container for the electrolyte and it is entirely leak-proof and may be used in radio sets without danger of electrolyte spilling or creeping to the outside.

To hold the electrolytic condenser in the radio set I preferably stamp a metallic base so as to cut out portions and leave projections 24. These projections are then bent downward as shown in Figs. 4 and 5 to form a socket, but the projections extend sufficiently toward the center to exert spring pressure on the container 1 of the condenser when it is forced into position. There is sufficient resiliency in the projections 24 to always insure that they will frictionally engage the container and hold it firmly in position. The container may be removed from the holder at any time by applying sufficient pressure in a reverse direction.

The notches 25, of which there are four, are preferably formed deep enough to extend beyond the bent-over strips 24 in Fig. 4 to give additional resiliency to these strips and to facilitate the stamping operation. The

hole 26 is made sufficiently large to accommodate the conductors that extend from the terminals 2 and 3 of the condenser to the other parts of the radio set. I have shown these wires in cross section at 28, 29 surrounded by the usual insulating material 30. Before the condenser is inserted in the holder the electrical conductor may be readily inserted through the large opening in the holder and then slipped through the slot 27 into the enlargement 26. This method is preferable to threading the conductors through the hole 26 after the condenser is in place.

The construction of the electrolytic condenser is not claimed herein as it is claimed in my copending application, Serial No. 513,261 filed February 3, 1931.

Having described my invention, what I claim is:

20. A holder for electrolytic condensers containing an opening and a small hole at one side of the opening, said opening and hole being connected by a channel for insertion of conductors, a pair of ears extending downwardly around the opening and separated by said channel, and additional ears extending downwardly around the opening and separated from each other and from the first mentioned ears by rounded openings in said holder said ears defining a socket slightly smaller than the condenser to be clamped therein.

In testimony whereof, I have signed my name to this specification this 9th day of January 1930.

35 THEODORE J. SCOFIELD.
